UNITED STATES PATENT OFFICE

LEO A. GUITERMAN, OF NEW YORK, N. Y.

TEE HOLDER

Application filed April 19, 1929. Serial No. 356,410.

This invention relates to clothing accessories. It is directed to an improved golf tee holder adapted to be carried by golfers and for the like purpose.

5 An object of this invention is to provide a tee holder of the character described which may be conveniently worn as part of the golfer's clothing, such as a sport garment having a pocket with a flap, and to which the tee holder may be detachably secured.

10 A further object of this invention is to provide a durable and neat device of the character described which shall be relatively inexpensive to manufacture which shall be easy 15 to attach and detach to the clothing, and which shall be practical and efficient to a high degree in use.

Other objects of this invention will in part 20 be obvious and in part hereinafter pointed out.

The invention accordingly consists in the features of construction, combinations of elements, and arrangement of parts which will be exemplified in the construction hereinafter 25 described, and of which the scope of application will be indicated in the following claims.

In the accompanying drawings, in which 30 is shown one of the various illustrative embodiments of this invention.

Fig. 1 is a front elevational view of a tee holder embodying the invention attached to a portion of a garment;

Fig. 2 is a cross-sectional view taken on 35 line 2--2 of Fig. 1; and

Fig. 3 is a front elevational view of a tee holder attached to a pocket provided with a flap adapted to be buttoned thereto.

Referring in detail to the drawings for 40 an embodiment of the invention, 10 designates a tee holder or magazine attached to a portion 11 of a garment adapted to be worn by a golfer for permitting ready access to said tees. Said holder comprises a front

45 portion 12 made of flexible material such as cloth, fabric, leather or any other suitable material, and a rear portion 14 of flexible lining or backing material stitched thereto along the perimeter thereof as by stitching

50 15. The outer edge portions 12a, 14a of said

portions 12, 14 respectively are preferably folded inwardly before the stitching operation to produce a smooth binding edge. Said portions 12, 14 are further sewed together as by stitching 16 along spaced parallel lines 55 terminating short of the top edge of the holder 10 and forming a number of narrow, elongated pockets 17. The front portion 12 of said holder is formed with a plurality of aligned preferably round openings 18, there 60 being one opening for each pocket 17, and said opening being disposed adjacent the upper ends of said pocket. The central portion 20 of the holder 10 may be somewhat wider than pockets 17 and provided with a button hole 21 65 extending thru said holder 10. Adjacent the upper end corners of the holder on the rear surface thereof, are secured a pair of snap fastener sockets 22, adapted to cooperate with complementary fasteners 22a, attached 70 to the garment portion 11. The golf tees 25 may be carried in the holder, by inserting the shanks 26 in the openings 18 to extend into the pockets 17, with the heads 27 of the tees protruding as shown in the drawings. 75

The holder 10 may be mounted on any convenient portion of the golfer's clothing having suitable snap fasteners 22a for cooperating with the socket portions 22. The holder may also be mounted on any portion 80 of the clothing having a suitable button for cooperating with the button hole 21. Preferably however, the holder is made in the shape of, though somewhat smaller than, a pocket lapel or flap, such as lapel 30 of 85 pocket 31, forming part of a jacket, shirt, coat or the like garment. The snap fastener portions 22a may be sewed to the sides of the pocket for cooperating with fastener portions 22 on the holder 10. Preferably 90 said pocket is provided with a button 32 for cooperating with button hole 33 of lapel 30. To ensure proper attachment to the garment, the holder 10 may be buttoned to said button 33. 95

It will now be understood that the tee magazine may be conveniently attached to the pocket and entirely concealed by buttoning the lapel, the top of the tees thus likewise being concealed from view. The 100

lapel 30 also serves to retain the tees in their pockets thus preventing accidental loss of said tees. By using the button 32 as well as snap fasteners, folding of the holder is prevented, the tees constantly being in position for removal for use.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth or shown in the accompanying drawings is to be interpreted as illustrative and not in a limiting sense.

Having thus described my invention I claim as new and desire to secure by Letters Patent:

1. In combination with a garment pocket having a button and lapel having a button hole for said button, a golf tee holder having a button hole adapted to receive said button for mounting said holder on said pocket and beneath said lapel.

2. In combination with a garment pocket having a button and lapel having a button hole for said button, a golf tee holder having a button hole adapted to receive said button for mounting said holder on said pocket and beneath said lapel, and snap fastening means for securing the outer edges of said holder to said pocket.

3. In combination with a garment pocket having a button and lapel having a button hole for said button, a golf tee holder having a button hole adapted to receive said button for mounting said holder on said pocket and beneath said lapel, said holder comprising a pair of superimposed pieces of sheet material of substantially similar shape having the edge portions thereof sewed together, and having a plurality of parallel lines of stitching defining pockets, and openings in one of said pieces to permit insertion of portions of said tees into said pockets.

4. In combination, a garment having a lapel, a golf tee magazine comprising a pair of similar superimposed pieces of flexible sheet material of substantially rectangular shape underlying said lapel and entirely covered thereby, said pieces being stitched together along the entire perimeter thereof, said pieces being further sewed together along a plurality of substantially parallel lines to define with said first named stitching a plurality of pockets, one of said pieces having openings for permitting insertion of a portion of a tee into each pocket.

In testimony whereof I affix my signature.
LEO A. GUITERMAN.
